UNITED STATES PATENT OFFICE.

ALBERT PETER, OF ST. LOUIS, MISSOURI.

SEWER-TRAP.

1,269,640.

Specification of Letters Patent. Patented June 18, 1918.

Application filed January 25, 1918. Serial No. 213,692.

To all whom it may concern:

Be it known that I, ALBERT PETER, a citizen of the United States, residing at St. Louis, State of Missouri, have invented certain new and useful Improvements in Sewer-Traps, of which the following is a full, clear, and exact description, reference being had to the accompanying drawings, forming a part hereof.

10 The present invention is particularly directed to the valve member of a sewer trap, the object sought being to provide a valve which shall positively seal or close the upper end of the waste pipe and thus effectively 15 prevent the backing of the sewer water into the trap and flooding the premises around the trap. A further object is to provide a construction which shall be sensitive and instantly responsive to the pressure of water 20 against it so that the back water may be choked off before it has a chance to pass by the valve. The advantages of the improvement will be better apparent from the following detailed description in connection 25 with the accompanying drawings in which—

Figure 1 represents a middle vertical section of a conventional bell trap having my invention applied thereto, the valve being shown seated or closed; Fig. 2 is a similar 30 view with the valve dropped to its lowest or open position; Fig. 3 is a top plan, with portions in horizontal section on the line 3—3 of Fig. 1; Fig. 4 is a bottom plan of the valve detached; Fig. 5 is a rear end view 35 thereof; Fig. 6 is a side elevation of the valve with the hinge portion in section; and Fig. 7 is a view similar to Fig. 2 showing a modification whereby the valve may be attached to existing traps.

40 Referring to the drawings, and for the present to Figs. 1 to 6 inclusive, 1 represents a catch basin from which leads the usual waste pipe 2, the said pipe projecting a suitable distance above the basin bottom as 45 shown. The basin is provided with the usual grating 3 from which depends the bell 4, said bell being disposed directly over the waste pipe 2 and terminating with its lower edge in a plane below the plane of the upper end of the pipe so as to form a water 50 seal as well understood in the art.

In the present embodiment of my invention, the intake end of the waste pipe 2 is closed by a perforated screw cap or filter 55 plate 5 as shown. Disposed on the inner wall of the pipe 2 below, and in proximity

to, the plate 5 is a lug 6 provided with a U-shaped recess r; said recess receiving the hinge pin or cross member 7 connecting the vertices of the triangular ears 8, 8, carried 60 by or formed on the float or disk valve V, the forward portions of the inclined edges of the ears 8, 8, being connected by a web 9 between the free edge of which and the hinge pin 7 is left an opening o through 65 which may be freely passed the finger 10 formed in the lug 6 as a result of the recess r. When the valve V is open (see Fig. 2) the hinge pin 7 rests in the bottom of the recess r of the supporting lug 6, in which 70 position the free edge of the web 9 comes into engagement with or bears against the finger 10, this engagement serving to arrest the valve and prevent the same from dropping to a vertical position. In other words 75 the valve is maintained in an inclined position so as to facilitate the lifting thereof by the water when the water from the sewer backs into the waste pipe 2. The valve in being lifted naturally will first swing to a 80 horizontal position about the hinge pin 7 as an axis, as indicated by the dotted position in Fig. 2, after which the water will pick up the valve bodily and force it into firm engagement with the plate 5, the hinge pin 7 85 under the circumstances being lifted slightly in its recess r as shown in Fig. 1. Thus the valve V is seated against the plate 5 not by an oscillating movement about the hinge pin 7, but by a bodily rectilinear movement or 90 motion of translation in a direction at right angles to the plate 5. By reason of this last movement the plane upper face of the valve is forced into intimate contact with the plane bottom face of the filter plate 5; and 95 since the valve engages the outer bounding imperforate portions of the filter plate, it follows that a water tight joint is formed between the plate and valve and no water can back into the catch basin 1. 100

To apply the invention to existing waste pipes 2' not provided with a lug 6, as shown in the modification in Fig. 7, I cut a thread on the inside of the waste pipe above the catch basin 1', and into the end of the pipe 105 thus threaded I screw a bushing 11 one end of which is closed by a filter plate 12, the bushing being provided with a marginal flange a which limits the distance to which it shall be driven into the pipe. In this 110 modification the lug 6' is formed on the inside of the bushing, said lug being provided

with a recess r' , a finger $10'$, and the valve V' being formed with ears $8'$, hinge pin $7'$ and web $9'$, these parts being identical with the corresponding parts in the form first described. In the modification, the member 12 takes the place of the member 5 in the form first described. It is obvious of course, that the structure is susceptible of further modification without a departure from the nature or spirit of the invention. The valve need not of course be restricted in its application to sewer traps.

Having described my invention what I claim is:

- 15 1. In a sewer trap, a waste pipe, a perforated filter plate mounted across the upper end thereof and provided with an outer imperforate portion, a lug in the pipe below the plate provided with a recess open at the top, a hinge valve provided with a hinge pin insertible in said recess, and a member on the valve interposed between the hinge pin and the valve body for engaging the adjacent wall of the recess and thereby arrest-
- 20

ing the valve and maintaining the same in 25 an inclined position in relation to the axis of the waste pipe.

2. A sewer trap valve comprising a disk, a pair of triangular ears disposed adjacent the edge thereof, a hinge pin connecting the 30 free vertices of the ears, a web spaced from the hinge pin and connecting the webs at points adjacent the valve body, a waste pipe, and a member in said pipe provided with an open recess for receiving the hinge pin of 35 the valve, the inner wall of the recess operating as a finger and positioned relatively to the adjacent edge of the web aforesaid for engaging said edge and thereby arresting the valve in its downward swing and maintaining it at an incline to the axis of the waste pipe.

In testimony whereof I affix my signature in presence of two witnesses.

ALBERT PETER.
